CLAIM

The ornamental design for a collapsible helmet, as shown and described.

DESCRIPTION

FIG. 1 is a top, front perspective view of a design for a collapsible helmet;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top, rear perspective view thereof;
FIG. 9 is a bottom, front perspective view thereof;
FIG. 10 is a bottom, rear perspective view thereof;
FIG. 11 is a top, front perspective view thereof, in a collapsed position;
FIG. 12 is a front view of FIG. 11;
FIG. 13 is a rear view of FIG. 11;
FIG. 14 is a left side view of FIG. 11;
FIG. 15 is a right side view of FIG. 11;
FIG. 16 is a top view of FIG. 11;
FIG. 17 is a bottom view of FIG. 11;
FIG. 18 is a top, rear perspective view of FIG. 11;
FIG. 19 is a bottom, front perspective view of FIG. 11; and,
FIG. 20 is a bottom, rear perspective view of FIG. 11.
The details shown in broken lines are for illustrative purposes only and form no part of the claimed design.

1 Claim, 20 Drawing Sheets
